UNITED STATES PATENT OFFICE.

PETER C. BURNS, OF CHICAGO, ILLINOIS, ASSIGNOR TO AMERICAN ELECTRIC COMPANY, OF CHICAGO, ILLINOIS.

AUTOMOBILE-HORN.

1,159,467.

Specification of Letters Patent.

Patented Nov. 9, 1915.

Application filed March 4, 1912. Serial No. 681,415.

To all whom it may concern:

Be it known that I, PETER C. BURNS, a citizen of the United States, residing at Chicago, in the county of Cook and State of Illinois, have invented a certain new and useful Improvement in Automobile-Horns, of which the following is a full, clear, concise, and exact description, reference being had to the accompanying drawings, forming a part of this specification.

My invention relates to horns and has for its particular object the provision of a new device of this character in which a diaphragm is operated by means of one or a plurality of impact devices, thereby to produce a loud sound through the agency of said diaphragm.

Generally speaking my improved device includes a diaphragm fixedly secured about its periphery which is associated with a suitable resonator or horn and in which I subject the diaphragm to a series of successive blows.

My invention concerns itself not only with a device of the character just outlined but also with new and improved mechanism for securing this rapid succession of blows to be given to the said diaphragm.

In carrying out one form of my invention I preferably mount an impact device rearwardly of the diaphragm in such a way that it may be symmetrically located with respect to the axis of the diaphragm. This impact device in the particular form of the device herein shown consists of a motor mounted rearwardly of the diaphragm whose armature carries the impact element or elements.

These and other features of my invention will be more readily apparent from the construction which I will now describe in connection with the accompanying drawings illustrating one embodiment thereof, in which:

Figure 1 is a side view partly in section of my improved horn; Fig. 2 is an end view looking to the right (Fig. 1) with the cover plate removed; Fig. 3 is a longitudinal sectional view on line *a*—*a* of Fig. 2, and Fig. 4 is a sectional view on line *b*—*b* of Fig. 1. In the particular embodiment of the horn illustrated herein, I utilize a resonator 1, which resonator is secured to a front plate 2. A diaphragm 3 circumferentially engaging the front plate is laid within the cup

shaped recess 3^a, strips of packing 4 being interposed. A back cup 5 is mounted in place as shown in Fig. 1, packing 6 being interposed and all of the elements 2, 3, 4, 5 and 6 are securely held together by means of the screws 7. This back cup has a cover plate 8 suitably held in place by the screws 9. The diaphragm 3 has a central opening 10 over which a suitable cover plate 11 is riveted. This diaphragm by means of its vibrations causes the noise or sound emanating from the resonator 1 as is well understood. In order to cause the vibration of this diaphragm I strike it a series of blows and these blows in the embodiment herein shown are struck through the agency of balls 12, which balls are circumferentially mounted within a carrier 13, said carrier having recesses 14 to accommodate said balls and having a ring 15 preferably of brass slipped over the outer periphery of said carrier to hold said balls within the recesses. This plate 15 however has openings large enough to permit the balls to protrude sufficiently far so that centrifugal force may throw them outwardly a distance sufficient to permit these balls to hit the diaphragm when this ring 13 is rotated. If the balls were to recede into their sockets they would normally not touch the diaphragm. This ring 13 carrying the balls is mounted upon an armature 16, which armature is carried by the shaft 17. This shaft 17 is mounted in bearings 18 and 19 suitably held in place in the side wall 20 of the back cup 5. It will thus be seen that if this armature is rotated, centrifugal force will cause the balls 12 to move radially outward into position to hit the diaphragm 3. Each ball hits the diaphragm a short space in advance of the opening 10 and this ball then immediately leaves the diaphragm after having struck its blow and is accommodated by the recess 10 until it leaves the close proximity of the diaphragm. This opening 10 is covered by the cover plate 11 so as to make a moisture proof front covering for the operating parts. The armature 16 is in association with two field pieces 21 carrying the windings 22, 22 and the side wall 20 of magnetic material forms the keeper for these pole pieces 21, 21. These pole pieces are recessed at 23 as illustrated so that these pole pieces accommodate the protruding ball

carrying ring 13. It will thus be seen that the armature is mounted transversely of these pole pieces as herein shown and the ball carrying plate rotates within a longitudinal recess provided in these pole pieces. 5 I am thus enabled to provide a symmetrical arrangement of these impact devices with relation to the containing cup 5 and the resonator 1. The armature is provided with 10 a suitable commutator 24 having the brushes 25, 25 to which current is supplied by means of binding posts 26, 26, the field windings 22 being also included in the circuit, all the elements in said circuit being preferably in 15 series relation. An arm 21 secured to the back cup 5 is used for mounting purposes.

In Fig. 4 I illustrate the means I employ to permit moisture which may enter by way of the resonator to escape without doing injury to the parts. It will be noted from an 20 inspection of Fig. 1 that the cup shaped angular extremity of the front plate 2 is larger in diameter than the outer periphery of the elements 3, 5 and 6 so that there is a 25 space between these elements 3, 5 and 6 and the element 2. The bushings 4 are cut in sections as shown in Fig. 4 and openings 30 left between adjoining bushings so that the moisture which collects between the elements 2 and 3 may fall downwardly between the intermediate spaces between the bushings 4 and then out through the space between the 35 elements 5 and 2.

I find that I can produce by means of the 40 device herein a very loud sound of particular utility, for instance, for automobile purposes and the loudness and quantity of the sound depends of course to some extent upon the number and violence of the impacts imparted to the diaphragm. In the embodiment 45 of the device herein shown the balls when farthest down in their recesses do not protrude beyond the plate 15, but when these balls are thrown out by centrifugal force they may protrude possibly a quarter of an inch, thus giving them a sufficient throw.

It will of course be understood that my invention is capable of broad application and 50 many variations may be made from the structure and arrangement herein without departing from the spirit of my invention.

Having however, thus described one form 55 which my invention may take, what I claim is new and desire to secure by Letters Patent is:

1. In a device of the character described the combination with a recessed diaphragm, a resonator therefor, means for striking said 60 diaphragm at said recess a plurality of successive glancing blows, and a motor having an armature for operating said means, said means being carried directly by the body of said armature.

65 2. In a device of the character described

the combination with a recessed diaphragm, a resonator therefor, rotatable means for striking said diaphragm at said recess a plurality of successive glancing blows, and a motor having an armature for operating 70 said means, said means being carried directly by the body of said armature.

3. A motor having field pieces and an armature, of an impact device carried by 75 said armature, and recesses provided in said field pieces to accommodate said impact device.

4. A motor having field pieces, and an armature, of an impact device carried by 80 said armature, and recesses provided in said field pieces to accommodate said impact device, said impact device carrying centrifugally controlled elements.

5. In a device of the character described 85 in combination with a resonator, of a diaphragm, centrifugal means for striking said diaphragm substantially at its center, and a prime mover for actuating said means, said prime mover being mounted substantially 90 symmetrical with respect to the axis of said diaphragm.

6. In a device of the character described in combination with a recessed diaphragm, of an impact device to strike said diaphragm at the edge of said recess, said recess extending 95 from the striking edge in the direction of movement of said impact device so that said recess accommodates said impact device in its further movement from said striking edge.

7. In a device of the character described, the combination with a diaphragm, a motor, an armature for said motor, a ring carried about said armature having a plurality of recesses, and impact elements carried 105 in said recesses and actuated by centrifugal force when said motor is operated, whereby said impact devices are adapted to strike said diaphragm.

8. In a device of the character described, 110 the combination with a diaphragm, a motor, an armature for said motor, a ring carried about said armature having a plurality of recesses, impact elements carried in said recesses and actuated by centrifugal force 115 when said motor is operated, whereby said impact devices are adapted to strike said diaphragm, and means for preventing said impact devices from being driven out of said recesses.

120 9. In a device of the character described, the combination with a diaphragm, a motor, an armature for said motor, a ring carried about said armature having a plurality of recesses, balls carried in said recesses and actuated by centrifugal force when said motor is operated, whereby said balls are adapted to strike said diaphragm, and means for preventing said balls from being driven out 125 of said recesses.

10. An alarm or signal apparatus of the class specified having a sound producing medium, and a motor having a rotary armature provided with a peripherally arranged means intermediate its ends for contacting with and operating said medium.
11. An alarm or signal apparatus having a vibrating medium, and a motor having a rotary armature, the body of the armature being provided with a plurality of projecting devices arranged to successively and directly contact with said medium.
12. An alarm or signal apparatus having a vibrating medium with a wear surface, an electric motor having pole members provided with inner grooves, and a rotary armature having projecting means and disposed between the pole members with the projecting means in the grooves, the projecting means of the armature directly contacting with the wear surface of the vibrating medium.
13. In a device of the character described the combination with a recessed diaphragm, of an impact device to strike said diaphragm at the near edge of said recess, said recess being of a size to prevent further contact of said impact device with said diaphragm in the further movement of said device and after the impact.
14. In a device of the character described in combination with a recessed diaphragm, of a centrifugally controlled impact device to strike said diaphragm at the edge of said recess, said recess extending from the striking edge in the direction of movement of said impact device so that said recess accommodates said impact device in its further movement from said striking edge.
15. In a device of the character described the combination with a recessed diaphragm, of a centrifugally controlled impact device to strike said diaphragm at the near edge of said recess, said recess being of a size to prevent further contact of said impact device with said diaphragm in the further movement of said device and after the impact.
16. In a device of the character described in combination with a recessed diaphragm, of an impact device to strike said diaphragm at the edge of said recess, said recess extending from the striking edge in the direction of movement of said impact device so that said recess accommodates said impact device in its further movement from said
- striking edge, and a motor carrying said impact device.
17. In a device of the character described the combination with a recessed diaphragm, of an impact device to strike said diaphragm at the near edge of said recess, said recess being of a size to prevent further contact of said impact device with said diaphragm in the further movement of said device and after the impact, and a motor carrying said impact device.
18. In a device of the character described in combination with a recessed diaphragm, of a centrifugally controlled impact device to strike said diaphragm at the edge of said recess, said recess extending from the striking edge in the direction of movement of said impact device so that said recess accommodates said impact device in its further movement from said striking edge, and a motor carrying said impact device.
19. In a device of the character described the combination with a recessed diaphragm, of a centrifugally controlled impact device to strike said diaphragm at the near edge of said recess, said recess being of a size to prevent further contact of said impact device with said diaphragm in the further movement of said device and after the impact, and a motor carrying said impact device.
20. An alarm or signal apparatus of the class specified having a sound producing medium, and a motor having a rotary armature provided with a peripherally arranged centrifugally controlled means intermediate its ends for contacting with and operating said medium.
21. A signal apparatus of the character described having a vibrating medium, and an electric motor having a rotary armature provided with projecting means forming a part of the body thereof, the said projecting means having direct contact with a portion of said medium.
22. In a signal apparatus, a vibrating medium, and a motor having a rotary armature, a portion of the body of the armature directly contacting with a portion of said medium.
- In witness whereof, I hereunto subscribe my name this 19th day of February, A. D. 1912.
